G. A. UHL

AIR OR SEAPLANE STATION

Filed Sept. 10, 1927

UNITED STATES PATENT OFFICE.

GEORGE A. UHL, OF SAN ANTONIO, TEXAS, ASSIGNOR OF ONE-THIRD TO GEORGE E. GINTER AND ONE-THIRD TO PHELPS & DEWEES, A FIRM COMPOSED OF RAYMOND PHELPS AND GEORGE DAHL DEWEES, ALL OF SAN ANTONIO, TEXAS.

AIR OR SEAPLANE STATION.

Application filed September 10, 1927. Serial No. 218,660.

The invention aims to provide a new and improved station for air or seaplanes, by means of which flights may be easily started or terminated, as required, and instead of necessarily making use of a rather long runway for either starting or stopping purposes, the invention embodies an elevated annular track, a carriage movable along said track, and a grapple carried by the carriage for engagement with another grapple on a plane. One form of grapple is used when a plane is to be started on a flight and the plane is supported by the grapple and the carriage and is driven under its own power beneath the annular track, until sufficient speed has been attained to allow the plane to safely take the air. Then, the flight-starting grapple is released, and the plane starts on its flight. For terminating a flight, another form of grapple is used and it is suspended from the carriage beneath the annular track so that when a plane is driven under said track and carriage, the grapple of said plane which projects above the latter, may be engaged with the flight-terminating grapple, allowing the plane to idly travel around beneath the track until it comes to a standstill. By suitable hoisting mechanism, planes may be raised for engagement with the flight-starting grapple or may be lowered from the flight-terminating grapple.

With the foregoing and minor objects in view, the invention resides in the novel subject matter hereinafter described and claimed, the description being supplemented by the accompanying drawing.

Fig. 1 is a perspective view of an air or seaplane station constructed in accordance with my invention.

Figs. 2 and 3 are detail transverse sections partly in elevation showing the flight-terminating grapple and the flight-starting grapple, respectively, in operative position.

In the drawing above briefly described, the numeral 5 denotes an appropriate mast or tower, at whose base a building 6 is preferably employed to serve as a hangar for planes, as a waiting room for passengers, as a plane service station, etc. Radiating from the upper end of the mast or tower 5, are a number of arms 7 which are rigidly attached thereto and carry an annular track 8 which

surrounds and is concentric with said mast or tower. Freely movable along this track 8 is a carriage 9 which carries both flight-starting and flight-terminating grapples 10-11, respectively. Either of these grapples may be disposed at an operative position below the carriage 9 for engagement with an arched bail or grapple 12 on the plane 13.

In the present showing, a right angular member 14 is pivoted to the carriage at 15 so that either of its ends may project downwardly from said carriage, while the other end then projects substantially horizontally. On one end of this member 14, the flight-starting grapple 10 is mounted and on the other end of said member, the flight-terminating grapple 11 is carried, said last named end being preferably provided with an appropriate shock-absorbing device 16.

The flight-starting grapple 10 preferably comprises a hook 17, a guard 18 for said hook, and electro-magnetic or other means for releasing said guard when desired. The flight-terminating grapple 11 preferably embodies a plurality of hooks 19 projecting in different directions.

When a flight is to be started the plane is elevated to a position directly under the carriage 9, by any preferred means not shown. The flight-starting grapple 10 is then pulled downwardly against the action of the counterbalance 14^a and engaged with the plane-carried grapple 12, and is held against accidental release therefrom by the guard 18. The plane may now travel around the mast or tower 5 under its own power until it has attained sufficient speed to permit of its safely taking off. Then, the guard 18 is released, electrically or otherwise, and consequently the grapple or bail 12 of the plane is freed from the hook 17, permitting the flight to be started safely and with ease. At the same time, weight 14^a restores member 14 to normal position with the grapple 11 disposed downwardly, preparatory to receiving an incoming plane.

When a flight is to be terminated, the plane is driven under the track 8, and its grapple or bail 12 engages one or another of the hooks 19 of the flight-terminating grapple 11. Then, the motor may be cut off and the plane allowed to drift around the mast or

tower 5, until it comes to a standstill. Then, the plane may be lowered by any desired means not shown.

The member 14 is of course easily swung 5 to position the grapple 10 at operative position, at the same time disposing the other grapple 11 in a position at which it will be entirely out of the way.

Excellent results may be obtained from the 10 general subject matter herein disclosed, whether used on land or upon ships, but it is to be understood that the present disclosure is for illustrative purposes only, and that within the scope of the invention as 15 claimed, numerous variations may be made.

I claim:

1. An air or seaplane station comprising a tower, a plurality of arms rigidly secured to and radiating from the upper end of said 20 tower, a continuous annular track supported rigidly by the outer ends of said arms, a carriage movable along said track, and a grapple hung from said carriage for engagement by another grapple member on the plane.
2. In an air or seaplane station, a carriage, 25 flight-starting and flight-terminating grapples, and means mounting said grapples movably on said carriage, said means permitting either of said grapples to move to an operative position at which it hangs from 30 the carriage for engagement with another grapple member on the plane.

3. An air or seaplane station comprising an elevated track, a carriage movable along said track, an angular member pivoted on 35 said carriage in a manner to permit either end of said member to project downwardly while the other end projects laterally from said carriage, a flight-starting grapple on one end of said member, and a flight-terminating 40 grapple on the other end of said member.

4. An air or seaplane station comprising an elevated track, a carriage movable along said track, an angular member pivoted on 45 said carriage in a manner to permit either end of said member to project downwardly while the other end projects laterally from said carriage, a flight-starting grapple on one end of said member, and a flight-terminating 50 grapple on the other end of said member, said last named end being provided with a shock-absorbing device.

5. An air or seaplane station comprising a vertically elongated tower, a continuous annular track around the upper portion of 55 said tower and spaced outwardly therefrom to permit planes to fly beneath said track, means rigidly supporting said track upon said tower, a carriage movable freely along said track, and a plane-engaging grapple 60 hung from said carriage.

In testimony whereof I have hereunto affixed my signature.

GEORGE A. UHL.
